UNITED STATES PATENT OFFICE.

HENRY B. BARDEN AND GEORGE H. CARVER, OF GRANVILLE, NEW YORK.

DESIGN FOR A STEAK-KNIFE AND CLEAVER.

SPECIFICATION forming part of Design No. 27,254, dated June 29, 1897.

Application filed March 16, 1897. Serial No. 627,885. Term of patent 14 years.

To all whom it may concern:

Be it known that we, HENRY B. BARDEN and GEORGE H. CARVER, citizens of the United States, residing at Granville, in the county of Washington and State of New York, have invented a new and original Design for a Steak-Knife and Cleaver, of which the following is a specification, reference being had therein to the accompanying drawings.

10 Our invention relates to a novel design for a steak-knife and cleaver which will possess advantages in point of efficiency and which will be clearly understood from the following description and accompanying drawings.

15 Figure 1 represents a side elevation of our steak-knife and cleaver. Fig. 2 is a vertical sectional view on the line X X of Fig. 1.

In the drawings, A designates the handle, to which is connected the blade, which is 20 formed with the central longitudinal ridges B, from which the blade tapers in opposite directions, giving the blade a diamond shape in cross - section, as clearly shown in Fig. 2. The blade is formed on one side with the short

25 curved edge C, forming a cleaver, and on the opposite edge with the long curved edge forming the steak-knife D. The cleaver merges in a deep curved portion E, which forms a point F, and directly under the curved portion E, through the body of the blade, is an 30 opening F'.

From the foregoing description and drawings it will be seen that we provide a steak-knife and cleaver in one implement, enabling a single article to perform the functions of 35 both in a thorough and perfect manner and at about the same price as would be paid for either of the articles separate.

We claim—

The design for a steak-knife and cleaver 40 herein shown and described.

In testimony whereof we affix our signatures in presence of two witnesses.

HENRY B. BARDEN.
GEORGE H. CARVER.
